UNITED STATES PATENT OFFICE.

SAMUEL GLOVER, OF ST. HELENS, AND JOHN WEST, OF SOUTHPORT, ENGLAND.

REGENERATOR-SETTING FOR VERTICAL RETORTS.

1,127,228.

Specification of Letters Patent.

Patented Feb. 2, 1915.

Application filed August 6, 1914. Serial No. 855,472.

To all whom it may concern:

Be it known that we, SAMUEL GLOVER and JOHN WEST, subjects of the King of Great Britain and Ireland, and residents of St. Annes, St. Helens, in the county of Lancaster, England, and Alton Lodge, Park Crescent, Southport, in the county of Lancaster, England, respectively, have invented certain new and useful Improvements in or 10 Relating to Regenerator-Settings for Vertical Retorts, of which the following is a specification.

This invention relates to regenerator settings for vertical retorts for the continuous 15 distillation of gas coal, shale or the like, of the type in which a plurality of separate or independent horizontal air heating and combustion chambers are arranged around the retorts, and has for its object to provide for 20 a more uniform and efficient heating of the gas coal or the like during the carbonizing process with economy of fuel, and for the more uniform cooling of the lower ends of the retorts.

25 Heretofore with vertical retorts heated in the ordinary manner, the walls of the retorts in any particular horizontal plane are subjected to very uneven temperatures, and as a result the coal or the like therein is not 30 uniformly carbonized and tends to travel downward at different rates at the opposite sides of the retort. Further excessively high combustion temperatures are necessary to insure a sufficient temperature for carbonizing 35 at all sides of the retorts and such high temperatures result in rapid deterioration of the retort walls.

40 Our invention comprises the improved construction and arrangement of retort settings hereinafter described and claimed.

45 Referring to the accompanying sheets of explanatory drawings which illustrate a vertical retort setting constructed in accordance with our invention:—Figure 1 is a sectional elevation of a retort setting. Fig. 2 is a cross sectional view on the line A A of Fig. 1. Fig. 3 is a sectional plan view on the line B B of Fig. 1. Fig. 4 is a sectional plan view on the line C C of Fig. 1. Fig. 5 is a sectional plan view on the line D D of Fig. 1. Fig. 6 is a sectional plan view on the line E E of Fig. 2. Fig. 7 is a sectional plan view on the line F F of Fig. 2. Fig. 8 is a sectional plan view on the line G G of Fig. 1. Fig. 9 is a sectional plan view 50 on the line H H of Fig. 1.

The same reference letters in the different views indicate the same parts.

The vertical retorts *a* pass through horizontal chambers *b*, *c*, *d*, the two lower rows *b* of which serve for heating the secondary air required for combustion in the combustion chambers *c*, and the upper rows *d* receiving the waste gases from the combustion chambers *c* and circulating it around the upper ends of the retorts to utilize the heat contained in the gases.

Each horizontal chamber around a row of vertical retorts is divided into two compartments and the gases are caused to travel in parallel streams through the said compartments. In the case of the lower chamber *b*, as shown in section in Figs. 3 and 4, the retorts have independent and non-communicating compartments *b*, *b*¹ at each side, 70 each compartment of the lower chamber (see Fig. 3) receiving a separate supply of cold air through passages *e*, *e*¹ and each compartment of the upper chamber (see Fig. 4) receiving a separate supply of partially heated air from the chamber beneath by way of the passages *f*, *f*¹ in the floors of the compartments. The heated secondary air then travels to vertical conduits *g*, *g*¹ (Fig. 4) which transfer it to the several 80 combustion chambers *c*. Each of the combustion chambers *c* is similarly divided into two compartments *c*, *c*¹ (see Fig. 5), the latter receiving independent supplies of heated secondary air and gas from the ports *h*, *h*¹ and *i*, *i*¹, the air traveling up the vertical conduits *g*, *g*¹ and the gas up the conduit *j*. It will be seen therefore that the products of combustion travel in parallel streams through the adjacent compartments 85 and that the heating of the opposite sides of the retorts is therefore practically uniform.

90 From the combustion chambers *c*, the products of combustion pass by way of the vertical flues *k* to the lowest of the three circulating chambers *d* shown in Figs. 6 and 7. The gases issuing from the ports *m*, *m*¹ in the said chambers, each of the latter being divided into two compartments *d*, *d*¹, 100 receive a supplementary supply of heated secondary air from the vertical conduits *g*, *g*¹ by way of the ports *n*, *n*¹ so as to insure the complete combustion of any unburnt gases which may pass into the chambers *d*, *d*¹ from the combustion chambers. From 105 the lowest row of chambers *d*, which we

term supplementary combustion chambers, the gases travel to the row above by way of the openings o , o^1 (see Fig. 8) and so to the openings p , p^1 (see Fig. 9). From the upper row of chambers the gases travel to the base of the chimney q (Fig. 9). The latter is divided by a division piece r for a distance up the chimney so as to equalize the draft in the chambers communicating with the two sides of said division piece.

It will be seen that throughout our improved setting, the air and gases are caused to travel in the same direction in two parallel streams on opposite sides of the retorts and we thereby insure not only a more uniform heating or cooling of the contents of the retorts and therefore a more uniform travel of the said contents down the retorts with greater efficiency of carbonization, but we are also enabled to reduce the initial temperatures in the combustion chambers and thus obtain economy of fuel and an increased life of plant.

Having now described our invention what we claim as new and desire to secure by Letters Patent is:—

1. In settings for vertical retorts, in combination, a plurality of horizontal chambers located at the sides of said retorts and means causing the air and gases which contact with said retorts for cooling and heating purposes to pass over the opposite sides of the retorts in two parallel streams moving in the same direction, as set forth.
2. In settings for vertical retorts, in combination, a plurality of horizontal chambers located at the sides of said retorts, a division piece dividing each chamber into two independent compartments, inlets and

outlets disposed at opposite ends of said compartments causing the air and gases to travel in parallel streams moving in the same direction, as set forth.

3. In settings for vertical retorts, in combination, a plurality of horizontal chambers forming secondary air heating, combustion, supplementary combustion and waste gas circulating chambers around said retorts, a division piece dividing each chamber into two or more compartments, inlets and outlets disposed at opposite ends of said compartments, means supplying parallel streams of air to each secondary air heating, combustion and secondary combustion chamber, and means supplying parallel streams of gas and waste gas respectively to each combustion and supplementary combustion chamber, as set forth.

4. In settings for vertical retorts, in combination, a plurality of horizontal combustion chambers located at the sides of the retorts, a division piece dividing each combustion chamber into two independent compartments, a gas supply conduit, gas ports in each compartment receiving gas from said supply conduit, secondary air supply ports adjacent to said gas ports, and waste gas outlet ports at the opposite side of the compartments to said gas and air inlets, as set forth.

In testimony whereof we have signed our names to this specification in the presence of two subscribing witnesses.

SAMUEL GLOVER.
JOHN WEST.
